[57] CLAIM

The ornamental design for a switch frame, substantially as shown and described.

DESCRIPTION

FIG. 1 is a front view of the switch frame, showing my new design;

FIG. 2 is a plan view of the switch frame as seen from the top;

FIG. 3 is a view of the switch frame as seen from the bottom;

FIG. 4 is a view of the switch frame as seen from the left;

FIG. 5 is a cross-sectional view of the switch frame taken along line 5—5 of FIG. 2; and

FIG. 6 is an enlarged perspective view of the switch frame, the toggle switch being shown in broken lines for illustrative purposes only.

A rear view of the switch frame is symmetrical with FIG. 1, and a view of the switch frame as seen from the right is symmetrical with FIG. 4, these figures are, therefore, omitted.
